UNITED STATES PATENT OFFICE.

ALBERT T. BISHOP, OF SOUTHBINGHAM, CONNECTICUT, ASSIGNOR TO THE HURWOOD MANUFACTURING COMPANY, INCORPORATED, OF BRIDGEPORT, CONNECTICUT.

TUBULAR LANTERN.

No. 855,443.

Specification of Letters Patent.

Patented June 4, 1907.

Application filed October 16, 1906. Serial No. 339,225.

To all whom it may concern.

Be it known that I, ALBERT T. BISHOP, a citizen of the United States, residing at Southington, county of Hartford, State of Connecticut, have invented a new and useful 5 Tubular Lantern, of which the following is a specification.

This invention relates to tubular lanterns, and particularly to that type of tubular lanterns in which the globe is raised and swung outward to facilitate access to the burner or to enable the globe to be removed from its guard or holder.

The object of the invention is to provide 15 an improved structure whereby the globe may be lifted and swung aside by a single continuous movement of an operating device such as a lever.

Another object of the invention is to provide 20 a lantern having a canopy for the globe, with improved means whereby the operation of a single device, such as a lever, will act through a sleeve to raise the canopy and globe, and then swing the globe aside while 25 the canopy simply remains raised.

To these ends, the invention consists in the construction and combination of parts substantially as hereinafter described and claimed.

30 Of the accompanying drawings, which form a part of this specification:—Figure 1 is a side elevation of a lantern embodying my improvements. Fig. 2 represents a section on line 2—2 of Fig. 1, and indicating by dotted lines the displaced position to which the globe may be swung. Fig. 3 represents a section on line 3—3 of Fig. 1, omitting the parts at and below the lower end of the sleeve.

40 Similar reference characters indicate the same or similar parts in all of the views.

From the base 10 of the lantern, the side tubes 11 and 12 extend upward in the usual manner and practically constitute portions 45 of the frame of the lantern, portions of an ordinary bail being shown at 13. The upper ends of the tubes 11 and 12 connect with the central tube 14 on which the canopy 15 is mounted to slide.

50 16 indicates an ordinary form of glass globe used in lanterns.

A sleeve 17 is mounted on the tube 12, and

an arm 23 is secured at its outer end to the bottom of the canopy 15, and is formed at its other end with a ring or partial ring 24 in- 55 closed by a curved tube or guide-way 22 formed on or secured to the upper end of the sleeve 17 so that said tube 22 serves as a coupling to connect the arm 23 to the sleeve 17 so that the sleeve can rotate on the tube 60 12 although the canopy and its arm only move vertically.

The rest 25 and the side arms 26 constitute a well known form of globe holder. The support for said globe holder comprises two 65 wires extending laterally therefrom and then upward to form two vertical portions 27, which constitute a guide-way for the operating lever hereinafter described. From the tops of the vertical portions 27, the wire ex- 70 tends horizontally as at 28, so as to constitute shoulders, the purpose of which will be presently described. The loop portion 29 of the globe holder support is secured to the lower end of the sleeve 17 so that said globe 75 holder will move vertically with the sleeve or be swung aside by said sleeve.

The operating device comprises, in the embodiment of the invention illustrated, a lever extending through the side tube 12 below the 80 sleeve 17 and having a curved or cam portion 30 extending between the vertical portions 27 of the globe supporting arm. The extreme end of the lever beyond the curved portion 30 terminates in a projection or hook 85 31, which is adapted to engage one of the shoulders 28 of the globe holder arm, as will be presently described. The other end of the lever is provided with a handle 32. A suitable catch 33 projects from the sleeve 17 90 in position to be engaged by the operating lever to normally hold it in the position shown in Fig. 1.

The operation of the device is as follows:— When it is desired to change the relative position of the parts from that shown in Fig. 1 to that indicated by dotted lines in Fig. 2, the first movement of the operating lever out of and away from the catch 33, causes the cam portion 30, running under the shoulder 28, to lift the sleeve 17 and also the canopy and globe-holder and globe, until the parts assume the position shown by dotted lines in Fig. 1. During this upward movement the

portion 30 of the operating lever extends through the guide-way formed by the vertical portions 27, so that the globe holder can not swing so long as said portion 30 of the lever is between said vertical portions 27; but when the parts have reached the position shown by dotted lines in Fig. 1, the lever no longer extends between the vertical portions 27, but its outer end or hook 31 engages the shoulder 28 of one of said portions 27, so that the final movement of the operating lever will cause the hook 31 to swing the entire mechanism, including the sleeve 17, and the globe holder, and globe, around to the position shown by dotted lines in Fig. 2. When the parts are in this position ready access is afforded to the burner, and the globe may be removed from the side arms 26. When the parts are to be returned to their normal position, a reverse movement of the operating lever first causes the outer side of the end of hook 31 to strike the other horizontal portion or shoulder 28 and first swing the globe support over the burner. A continuing movement of the lever in the same direction permits the globe and globe holder to descend. The final movement of the lever under the catch 33 acts to lock the parts in normal position for use, the lever being held by the catch with sufficient firmness to insure the parts remaining normally in the position shown by full lines in Fig. 1 until the operator desires to raise the globe.

It will now be understood that I have provided a simple and economical structure whereby a single movement of the operating lever in one direction will first place the parts of the lantern in a position to permit the globe to be swung, and then to swing said globe, while a single return movement of the lever restores all parts to their normal position and locks them there. Both operations may be very quickly effected and the movements of the connections must take place in their proper sequence so that there can be no possibility of their getting out of order.

Having now described my invention I claim:

1. A lantern including in its construction a globe holder having both a slidable and rotatable connection with a vertical side portion of the frame of the lantern, an operating lever, and connections whereby said lever will first raise the globe holder and then

swing it bodily aside on a substantially vertical axis. 55

2. A lantern including in its construction a sleeve mounted to slide and oscillate on a portion of the frame, a globe holder rigidly connected with the sleeve, an operating lever, and connections whereby said lever will first raise the globe holder and then swing it aside. 60

3. A lantern including in its construction a sleeve mounted to slide and oscillate on a portion of the frame, a globe holder rigidly connected with the sleeve, an operating lever mounted below the sleeve, and connections whereby said lever will first raise the globe holder and then swing it aside. 70

4. A lantern including in its construction a sleeve mounted to slide and oscillate on a portion of the frame, a vertically movable canopy connected with the upper end of the sleeve, a globe holder rigidly connected with the lower end of the sleeve, an operating lever, and connections whereby said lever will first raise the sleeve, canopy, and globe holder and then swing the latter aside. 75

5. A lantern including in its construction a sleeve mounted to slide and oscillate on a portion of the frame, a vertically movable canopy, a globe holder rigidly connected with the lower end of the sleeve, a guide-way at the upper end of the sleeve, an arm extending from said guide-way to support the canopy, an operating lever, and means whereby actuation of the lever will raise the sleeve and canopy and globe. 85

6. A lantern including in its construction a sleeve mounted to slide on a portion of the frame, a vertically movable canopy connected with the upper end of the sleeve, a globe holder, an arm connecting the lower end of the sleeve with the globe holder, said arm having a vertical guide-way and shoulders, and an operating lever fulcrumed below the sleeve and having a cam portion extending through the vertical guide-way of said arm and provided with a terminal hook to engage one of said shoulders to swing the sleeve and globe holder. 95

In testimony whereof I affix my signature, in presence of two witnesses.

ALBERT T. BISHOP.
